UNITED STATES PATENT OFFICE.

BENJAMIN F. FITCH, OF EVANSTON, ILLINOIS, ASSIGNOR TO THE MOTOR TERMINALS COMPANY, OF CLEVELAND, OHIO, A CORPORATION OF OHIO.

TRANSFER SYSTEM FOR FREIGHT-TERMINALS.

1,275,145.

Specification of Letters Patent. Patented Aug. 6, 1918.

Application filed February 12, 1917. Serial No. 148,075.

To all whom it may concern:

Be it known that I, BENJAMIN F. FITCH, residing at Evanston, in the county of Cook and State of Illinois, have invented a new and useful Improvement in Transfer Systems for Freight-Terminals, of which the following is a full, clear, and exact description, reference being had to the accompanying drawings.

10 In the transportation of package freight, involving less than carload lots to any destination (commonly called "L. C. L. package freight") it is necessary at one or more intermediate points on the route of the freight 15 to break bulk and remove some or all of the freight from the cars containing it, and transfer it to sub-stations or to other cars for forwarding line movement. In accomplishing this, the prevailing operating practice is, after the cars have arrived at freight 20 terminals, or transfer or "break-bulk" points, to truck the freight from such cars over the station or transfer platforms to cars spotted on the same or adjacent rails, 25 or sometimes to truck the freight from the receiving cars to the station floors and again truck it to transfer cars. These transfer cars are destined either to terminal stations at other points on the receiving line or to 30 sub-stations in the same terminal territory, or through yard clearance to terminal stations or transfer platforms of forwarding lines, for similar rehandling into their "destination cars" or "break-bulk cars."

35 Since freight stations are ordinarily operated for convenience of consignee and consignor on a single shift, day schedules are arranged for early A. M. arrival of trains on their inbound movement and P. M. 40 departure on their outbound movement. This usually requires the spotting or placing of the transfer or trap cars at platforms before morning arrival of freight house men to perform the unloading operation. As such unloading generally occupies the working day it prevents the trap 45 or transfer cars on their outbound or switch movement from being switched and pulled from the freight house, or transfer platform, until the operation of checking, unloading, trucking and loading is completed in all cars. This results in night 50 switching of such cars for the following day's delivery and spotting or placing at

substation platforms of the same road, or 55 platforms of the forwarding line.

Moreover, since freight at out-bound platforms of all freight houses during the station working day is received from consignees for loading into the trap or transfer cars and "break bulk point cars", which are of necessity interspersed on rails adjacent to the platform in the station makeup, the switching of both inbound and outbound cars is delayed until receiving, checking, 60 trucking, loading and stowing of freight is completed at end of the station operating day.

As a result, freight actually arriving at terminal stations or transfer points in the 70 early morning hours of the first day is moved the current night, in the trap cars to which it has been transferred, to sub-stations for delivery to consignee the second day, or to forwarding lines for similar 75 rehandling into their destination cars. The reverse movement being the same, consignee and consignors, receiving and delivering freight from and to the outlying stations, of any large city or terminal point, suffer at 80 least a twenty-four hour delay, and all freight to forwarding lines in its through routing, a thirty-six hour delay.

On account of terminal trackage congestion, this delay between stations is frequently 85 indefinitely prolonged and resultingly accumulative. This condition is largely responsible for existing terminal freight congestion at all points, and accounts for the slow movement of through freight. Such delayed 90 freight, either in cars alongside the station platforms or in terminal freight yards, occupies the most valuable realty of any railway system, and frequently such terminal facilities could only be increased at prohibitive cost. 95

To do away with the delay incident to this intracity or forwarding line transfer, as well as to reduce the expense of the transfer, I have conceived a plan whereby the "L. C. L." package freight, arriving at inbound or 100 outbound platforms of terminal stations or at transfer platforms, may be immediately loaded direct from car into automobile trucks and transferred over the city streets to the destined substation, or forwarding 105 line platforms, and vice versa. Thus it reaches destination a short time after the unloading of break bulk point cars.

For carrying out such plan, I have devised a simple and effective combination of removable and interchangeable truck bodies and trolley hoisting mechanisms, associated with 5 railway platforms and automobile runways, whereby arriving freight may be immediately trucked across the platform into various removable motor truck bodies, assigned to various destination points, such bodies, 10 when loaded, being moved by the trolley hoists onto awaiting trucks, and at once driven to destination station, or a transfer platform of the forwarding line. This destination station or transfer platform being 15 likewise equipped with trolley hoisting mechanism the arriving loaded body may be at once removed from the truck and spotted for unloading, and the truck frame thus freed to receive and transport a new loaded 20 body.

In applying my transfer system I may utilize so much of an existing freight terminal, station or transfer platform as provides rails, one or more platforms parallel 25 therewith on a hand-trucking level with floors of the freight cars on rails, and a space for vehicles on the opposite side of the platform. With such existing facilities I arrange trolley hoists on tracks which extend 30 over a vehicle space or runway, which will accommodate motor trucks. The trolley tracks are preferably arranged in pairs and the hoisting mechanism thereon is arranged to raise two lift chains, so that each removable 35 truck body may be supported at points corresponding to its four corners.

Ordinarily, I prefer to extend the various trolley tracks at right angles to the station platform, over a parallel runway, and, in 40 such an installation, the removable bodies supported by the different trolley hoists may be suspended in a row along the automobile side of the freight platform. Each trolley trackway may sometimes be provided with 45 a second set of hoisting mechanism, so that when an automobile truck with either an empty or loaded body comes into the automobile driveway, the body may be lifted therefrom and transferred away from the 50 driving frame of the motor truck by one set of hoists, and a loaded body may be moved onto the standing motor truck chassis by the other set of hoists. Then, after the truck has moved away with its load, the newly received body may be trolleyed over adjacent 55 to the platform to be unloaded, if filled, and reloaded.

To increase the flexibility of the system, I prefer to extend the trolley tracks transversely over all or a portion of the freight platform, and to provide each movable body with small wheels, whereby it may be readily rolled on the station platform by hand or any suitable power mechanism. By this 60 means the body can be lifted onto the plat-

form and then moved into juxtaposition to a freight car door for direct unloading of large lots, thus shortening the hand-trucking distance, or it may be rolled longitudinally on the platform beneath another 70 trolley trackway. This provision renders the available space and trolley equipment more adaptable for the varying conditions of freight movement or in the arrival and departure of the automobile trucks, thereby 75 preventing congestion at any one point on the platform.

My invention, including the method of transferring freight above referred to and apparatus for carrying it out, is hereinafter 80 more fully described in connection with illustrated freight terminals and stations. As shown in the drawings, it offers opportunity for application in various ways, as may be made necessary by station locations 85 in relation to streets, and construction of such stations. In the following description various features will be explained which contribute to the efficiency of the general system as above outlined. While the specific embodiment is comprised within my invention, I do not intend to limit myself to such embodiment, as the particular arrangement of freight houses will vary with local conditions. The essential characteristics of my invention are summarized in the 90 claims appended hereto.

In the drawings, Figure 1 is a diagrammatic plan illustrating my transfer system as applied to several track-terminals and 100 one "off-track" terminal. This figure illustrates at the different terminals various arrangements of the platform and trolley hoists. Figs. 2, 3 and 4 are plans illustrating the terminal stations designated A, B and C respectively, in Fig. 1; Figs. 5, 6 and 7 are cross sections of the stations A, B and C respectively; Fig. 8 is a side elevation of one of the automobile trucks with a removable body, together with the trolley hoists 105 for raising and transporting the latter; Fig. 9 is a plan of such truck with the body in place; Fig. 10 is a bottom plan of the body; Fig. 11 is an enlarged end view of the truck with the body raised above the truck 110 frame by means of the trolley hoists; Fig. 12 is a sectional end view of a trolley hoisting mechanism, as indicated on the line 12-12 of Fig. 11; Fig. 13 is a side elevation of a portion of the trolley hoisting mechanism shown in Fig. 12; Fig. 14 is a detail 115 illustrating the racking mechanism on the trolley, this view being a sectional elevation on the line designated 14 in Fig. 12.

In Fig. 1 of the drawings, I have illustrated four track freight-houses, A, B, D and E, and one "off-track" terminal designated C. The stations A and E are illustrated as being on the "A & E" Railroad. Station B is supposed to be on the "B & B" 120 125 130

Railroad, and station D on the "D & D" Railroad. A belt-line is illustrated as connecting with different railroads. T indicates a telephone exchange which is shown 5 as located at the off-track terminal C. From this exchange, private telephone lines extend to each freight terminal. The broken lines bearing the legend "Truck route" indicate city streets or roads along which the 10 automobile trucks may conveniently travel from any station to any other.

The stations shown in this view differ specifically from each other and therefore will be specifically described hereinafter. 15 Each station, however, illustrates the general principle involved in the invention. The trolley hoisting mechanism is the same at each station, and it will be convenient to describe it in connection with the description 20 of first station; then I will follow with a brief description of each of the other stations illustrated.

Referring first to Figs. 2 and 5, which illustrate station A, which has much in common with the other stations, 10 indicates the platform of the freight station and 11 the roof therefor, supported by posts 12. Along one side of the platform is a railroad track 8 on which freight cars 9 may stand, and 25 on the other side is the vehicle space or runway, designated 14. The supports for the trolley hoists are shown as girders or I-beams 15, extending over the vehicle runway and the adjacent portion of the platform, at right angles to the platform. These 30 girders are shown as supported by the posts 12 at their inner ends, and at their outer ends by posts 16. On the girders are suitable trolley hoists 17 adapted to support removable truck bodies 18. 19 indicates the truck proper or chassis for carrying the bodies.

The I-beam trackways 15, in this installation, are arranged in pairs, and on each 45 trackway are a pair of trolley hoists 17, each of which has two lift hooks carried by two laterally spaced lift chains. There is thus provided for each loading or unloading position on the vehicle side at least four 50 lift chains adapted to engage the truck body at points corresponding to its four corners, whereby the body may be efficiently supported, as well as raised and lowered.

For convenient shifting of the bodies, I 55 prefer to provide at least two of these twin hoisting mechanisms for each I-beam, as shown in the drawing. This enables the simultaneous support of two automobile bodies, and the shifting of one body from the truck proper, and the placing of another body thereon. This will be better understood from the description of the general operation, following the description of the hoisting mechanism shown.

60 Referring more particularly to Figs. 8

and 11 to 14, it will be seen that each of the twin-hook trolley hoists 17 comprises two supporting trolleys 20 and 21, tracking on the I-beam 15, a beam 22 supported by these trolleys, a power mechanism 23 supported by the beam, a shaft 24 supported by the beam and adapted to be rotated by the power mechanism, pocket wheels 25 and 26 on the shaft, and lift chains 27 and 28 extending over the pocket wheels. As shown 70 the lift chains carry movable pulleys 29 which support the hooks 30, the end of the chain being anchored to the support and depending in a loop through the movable pulley. Each hook 30 is shown as supporting 75 a single chain 31 terminating in a hook 32 which engages an eye 58 in a floor beam 59 secured to and supporting the removable truck body 18, hereinafter described.

Such a structure as described provides two 80 lift chains raised or lowered as a unit and adapted to engage the opposite ends of the transverse body-beam 59 and support the removable body at that end, and raise or lower it, as desired.

90 It is convenient and efficient to make the beam 22 of the traveling hoist mechanism in the form of a horizontal channel bar with downwardly extending flanges. Two bearing blocks 34 for the shaft 24 are shown as 95 extending within the flanges of the channel and secured thereto by bolts 35. Each bearing block has a removable bearing cap which may be held by the same bolts.

The power mechanism for rotating the 100 shaft may be of any suitable form. I have shown for this purpose what is known as a "Cyclone" hoist, except that in place of the usual support hook the frame is secured directly to the channel beam, and in place 105 of the usual lift wheel, the shaft 36 (Fig. 11) therefor extends through the frame in alinement with the shaft 24, and is connected with it by a dental coupling 37, allowing some play and preventing binding 110 of the shaft in its bearings.

The construction of the "Cyclone" hoist which is employed as the power mechanism, is described and claimed in Patents Nos. 757,333 of April 12, 1904; 794,997 of July 115 18, 1903, and 946,253 of January 11, 1910, to E. Y. Moore. For the purpose of the present invention, however, it is only necessary that this power mechanism provide efficient means for transmitting the rotation 120 of a hand wheel 38, at much reduced speed and correspondingly increased power, to the shaft 24. A suitable hand chain 39 extends over this hand wheel and thus furnishes the means by which the movable pulleys 29 are 125 raised or lowered.

Each of the trolleys 20 or 21, which support the beam 22 of the twin-hook hoist, consists of four wheels 40, tracking on the I-beam, and a suitable frame carrying such 130

wheels and extending from the outer sides thereof downwardly and meeting beneath the I-beam. This frame is shown as connected by a pivot 42 with a bracket 43, bolted 5 to the upper side of the channel bar 22. Preferably the same bolts which secure the bearing brackets 35 and their caps to the beam on its under side secure the beam to these upper brackets 43. The pivotal connection 10 between the trolleys and the frame of the twin hoist prevents strains due to any irregularities in the trackway, and insures the twin-hook hoist being supported by all the wheels of both trolleys.

15 To mechanically shift the hoist in and out, or "rack" it, as it is termed, to transfer the supported truck body laterally, I adopt means for rotating wheels of one of the trolleys. As shown, the trolley nearest the 20 power mechanism 23 has two of its wheels on the same side provided with gear teeth 45, Figs. 12-14. These teeth mesh with a pinion 46 on a shaft 47 journaled in the trolley frame and provided on its outer end 25 with a hand wheel 48. A hand chain 49 running over this hand wheel furnishes convenient means for rotating the hand wheel and thereby rotating the two wheels geared with it, thus causing the whole hoist to 30 travel in or out on the I-beam, as desired.

The above described construction of twin-hook trolley hoist is the invention of Mr. E. Y. Moore, and will be claimed in an application to be filed by him. As far as my invention 35 is concerned it is to be deemed illustrative of any dual trolley hoist adapted to travel as a unit on an I-beam and provide two laterally spaced lift chains operating simultaneously.

40 It will be seen that by the construction described, employing twin-hook hoists on two adjacent I-beams, I may support the body of an automobile truck at four points, and raise or lower that body. In the operation 45 of my system, empty truck bodies are thus each supported by two of the twin-hook hoists on the vehicle side of the platform. When such truck bodies have been loaded, they are, by the aid of the trolley hoists, mounted on the truck frames and driven away. This may be accomplished by 50 raising the loaded body and driving the truck frame beneath it and lowering the body into place, or the truck may be driven 55 to a position alongside of the body and the body moved laterally by the racking operation of the trolleys to carry the body over the truck frame. Frequently the operation would be a combination of the raising, racking 60 and lowering.

It should be noted that while the two lift chains on each twin-hook hoist are raised as a unit, the two twin-hook hoists of a pair are entirely independent, both in their raising 65 and racking movements. The result of

this is that when a removable body is engaged either end thereof may be raised or lowered or moved laterally, independently of the other end. This enables me to turn the body askew or tip it toward either end 70 to allow its ready placement on a motor truck frame which is out of parallelism with the platform or does not stand level. The same independence of operation enables me to readily remove the truck bodies from 75 such inaccurately positioned motor trucks. The latitude thus allowed in positioning the motor truck is of importance in enabling rapid operation.

By moving together the two chains at 80 each end, by the twin-hook hoist described, I insure the proper support for the truck body, and it is impossible to throw an undue strain on any lift chain, such as might result if the four lift chains associated with the 85 body were all operated independently of each other. It will be seen, therefore, that I obtain a very valuable result by combining unity of operation of the two lift chains associated with the same end of the body, 90 with independence of operation of the hoisting means for the two ends.

The removable bodies 18 may be greatly varied in combination so long as they are adapted to be raised, lowered or trolleyed 95 by the hoisting mechanism described, and may be conveniently loaded and unloaded. The body illustrated in Figs. 8 to 11 is deemed satisfactory, however, and will now be described. As shown in these views, 100 50 indicates the floor of the body supported on transverse beams 51 connected at their ends by longitudinal members 52. These members 52 have secured to them the brackets 59 to which the chains are connected. Rising 105 from the corners of the floor, and from intermediate positions at the sides, are suitable vertical posts 54 and 55 respectively. These posts are connected above by longitudinal 110 and transverse beams 56 and 57.

The body is preferably open at the ends and at the middle portion of the two sides. These parts may readily be sufficiently closed by vertical members (preferably hollow pipes) 60, which are loosely guided at their 115 upper ends by the beams 56 and 57 and at their lower ends rest in sockets provided by the end beams 62 and side members 63. Accordingly, by slightly raising these pipe members they may be freed from their sockets and drawn out of the upper beam to open the doors either in the ends or the sides of the body. The body is preferably provided with a ridge pole 65 supported by inclined bars 66 on the sides. A suitable canvas thrown over this ridge pole provides protection for the goods in wet weather.

The truck 19 is preferably provided with a floor 70 on which the removable body may rest. This floor is shown as supported on 130

transverse beams 71 resting on longitudinal stringers 72 carried by the chassis frame. Extending around the edge of the floor 70 and rising from it, is a guard wall 74, preferably made by angle bars secured to the floor 70. This metal wall protects the body from damage and enables the truck to drive into contact with the edge of the station platform without endangering the body.

10 The wall 74 is interrupted at 75 to allow the body-supporting member 59 to project to the outside. To accurately position the body on the truck and hold it against movement thereon, when placed, I provide on the 15 under side of the body a number of tapered downwardly projecting blocks 67, which are adapted to extend through holes 76 of proper size and position in the floor. There are also holes or pockets, 78 and 79 in the 20 floor of the stationary truck body to accommodate rollers on the removable bodies (hereinafter referred to), so that such bodies rest flush on the stationary truck body.

As heretofore stated, it is frequently desirable to rest the bodies on the freight platform and shift them longitudinally thereon, to clear a certain loading position or bring them beneath other I-beam trackways, or to shift them laterally to spot them directly adjacent to a car door for direct transference of freight. To enable this shifting to be performed conveniently, I provide each body with rollers or wheels. I have shown two of such rollers 68 at the middle of the longitudinal center of the body near the sides, and two rollers 69 at intermediate positions near the ends. The side rollers 68 are preferably ordinary wheels mounted on roller bearings, while the end rollers are roller bearing casters. This construction enables the body to be shifted on the platform by hand or by the employment of any suitable tractor or windlass mechanism, as desired.

As heretofore referred to, the trolley hoisting mechanism is the same at each of the stations illustrated. The arrangement of the station, however, and the support for the track rails differs with the different installations. Station A has been described. 50 Station B, illustrated in Fig. 1, is shown more fully in fragmentary plan in Fig. 3 and in cross section in Fig. 6, and will now be described.

Station B has two station platforms 10^a and 10^b, respectively, on a hand-trucking level with freight cars 9^a and 9^b on the two tracks 8^a and 8^b. The freight platform 10^b is shown as on the same level with the intermediate automobile runway 14^a, which may 55 be a city street. 11^a indicates a roof which may be supported by posts 12^a and 12^b and extend over the automobile runway. At 60 each side of this roof is shown a shed roof 11^c and 11^b supported at the outer edge by 65 posts 12^c and 12^d respectively.

At one side of the freight house B is shown a pair of I-beams 15^a supported by posts 12^a and 12^c and by tie rods 90. This pair of I-beams extends over the platform 10^a and out over the vehicle space, as shown in Fig. 70 6. It is adapted to support two or more removable bodies 18 over the platform 10^a and one body overhanging the runway, as shown. On the other side of this freight house I have shown I-beam trackways 15^b 75 extending parallel with the platform and over it and carried by the transverse girders 91, supported by the posts 12^b and 12^d. These I-beams are adapted to support hoisting twins shiftable lengthwise of the platform 80 and these hoists may support a removable body 18, which thus extends at right angles to the line of freight cars 9^b.

The arrangement of this station B enables the arriving truck to run directly beneath the overhanging I-beams 15^a for the removal or placement of its body, or it can back into the bay where the I-beams 15^b are located. In the latter position it will be standing at right angles to the railway track. 90

In the usual operation of such a station as shown in Fig. 6, one of the platforms is for inbound freight and the other for outbound freight. It is convenient to have the automobile traffic only in one direction between the platforms, as indicated by the arrows in Fig. 1. If we assume that the platform 10^a is the outbound platform, the driver arriving with the loaded truck will come into the bay, where the longitudinal 100 I-beams 15^b are located and discharge the loaded body and then will drive forward on a curve to a point alongside of the platform 10^a beneath the overhanging portion of the I-beams 15^a, where a loaded body may be 105 trolleyed from over the platform beyond the edge thereof and there deposited on the truck frame for immediate despatch. In this installation the surplus bodies trolleyed back over the platform 10^a or along the platform 110 10^b, may be lowered onto the platform and rolled out of the way, by reason of the wheel supports of the body, before referred to.

The arrangement described for station B is convenient for a terminal where the railroad track is depressed below the street level and one of the platforms is on the same level with the street. In such an installation there is liable to be freight standing in various positions within such street as it is 115 dumped from arriving vehicles (as shown at F, Fig. 3) and it is important not to interfere with such deposit of freight.

Fig. 1 illustrates at C an "off-track" or "inland" terminal, arranged to receive 125 freight from shippers and deliver freight to consignees, and equipped with my trolley hoisting features to efficiently cooperate as a unit in my transfer system. Referring particularly to Figs. 1, 4 and 7, 130

it will be seen that the freight house C comprises an outbound platform 10^c, an inbound platform 10^k, with an automobile runway 14^e between them, and team space 6^a and 6^b on the outer sides of the two platforms. The platforms are preferably of the saw-tooth type, arranged to accommodate a large number of vehicles which drive in a definite direction in the team traffic way and back into the saw-tooth bays, enabling ready loading or unloading at the rear or side of the vehicle. One such vehicle is illustrated at 5, Fig. 4.

Extending across the vehicle space 14^e are numerous I-beams 15^e, arranged in pairs. These I-beams carry twin-hook hoists which coöperate to raise and shift removable bodies 18, as already explained. The I-beams extend over the inbound platform 10^k and are thus adapted to deposit their bodies on this platform. Some of these I-beams are shown as cantalivered beyond their supporting posts at the edge of the platform, and others as extending still farther across the platform and supported by additional posts at their ends.

It is very convenient to combine this off-track terminal with a railway storage warehouse having a plurality of stories and provided with elevators, so that when freight is received from other stations and the consignee is not ready to receive it, a removable body containing it may be simply rolled on the platform 10^k to one of the elevators, indicated at 95, and raised to another floor for storage. This off-track terminal is shown as provided with inclosing walls 92, and may have various floors, as indicated at 93 and 94, above the platforms and over the automobile runway.

The possibility of using one or more off-track terminals in my transfer system is one of its valuable features, as will be seen from the following considerations. Railroads in the past have invested enormous sums for rights of way and terminal realty in all large cities, to provide freight stations located as conveniently for shippers as the topography and arrangement of the city would allow. This has been with a view to providing a short haul from the shipper to the railroad terminal. One result, however, has been to make the territory in the immediate vicinity so valuable that the railroad cannot afford to expand at that terminal when congestion demands it. The resultant high prices of the adjacent land has also driven manufacturers and others to seek locations in outlying territory.

By my system of an off-track terminal, the railroad may expand as much as necessary without either acquiring expensive realty adjacent to its own terminals or purchasing an expensive right of way in a city to a new terminal. Furthermore, my off-track terminal

nals may be located in very convenient spots where grades and other conditions make it practically impossible for a railroad track to be laid. By combining this off-track terminal with a storage ware-house, great convenience is provided both for the railroad and for shippers, and the storage charges provide considerable revenue for the railroad.

In the operation of the off-track terminal shown in Figs. 4 and 7, it is proposed that the outbound platform have empty bodies suspended on its hoists next to the inner edge or truck driveway for the full length of the platform, the floors of these bodies being on the platform level. As the wagons with freight to be shipped enter the team traffic way 6^a, in the direction of the arrows, they can back with the least possible delay into empty saw-tooth pockets and unload their freight, which may be hand-trucked, as indicated by the direction lines in Fig. 4, direct to the bodies assigned to the different freight stations comprised within the system.

In the meantime, at the various railroad track terminals, freight arriving from freight cars has been installed in removable bodies which are loaded and hauled to the off-track terminal. Now, as the loaded truck enters the central portion of the off-track terminal shown, it proceeds to some location opposite a point where no removable body is suspended adjacent to the inbound platform. The chains of the overhead hoists are then hooked onto the body which is on the truck and the same is moved to the edge of the inbound platform for unloading, and a loaded body is shifted laterally from the outbound platform over the truck, and the latter proceeds to the railway terminal designated by the billing of the freight contained in the newly placed body.

Now, the consignor's wagon or truck which has discharged its load in a saw-tooth pocket of the outbound platform, may drive out of the station and, follow the line of traffic and enter the team traffic way 6^b, back up into one of the pockets of the inbound platform and receive freight destined for such consignee.

Whenever freight received at the off-track terminal cannot be conveniently received by the consignee, the body it occupies, or another body to which it is transferred, is simply raised to the platform, rolled on the platform to the elevator, and stored until the consignee is ready to receive the freight.

In the normal operation of my off-track terminal the newly received freight bodies, after being unloaded at the inbound platform, will be simply trolleyed across to the outbound platform to receive a fresh load. However, as may often occur, the unloading process at the inbound platform will not balance in time duration with the loading at

the outbound platform. This difference is readily relieved by rolling the empty bodies along the inbound platform beneath available pairs of I-beams by which they may be 5 trolleyed over against the outbound platform.

The off-track terminal illustrated in Figs. 4 and 7 and above described, is one of the component units in the transfer system 10 claimed herein. This terminal freight house is also individually an invention of mine, and may be specifically claimed in an application to be filed hereafter.

Fig. 1 of the drawings shows stations D 15 and E specifically different from any of which have been described, but which are not deemed to need more detailed showing. Station D is designed where there is width in the automobile runway 14^a for only two 20 truck bodies. The I-beam trackways 15^a extend over this automobile runway and over a portion of the platform 10^a. This enables the convenient shifting of the loaded and empty bodies to either side of the automobile 25 truck which stands adjacent to the platform.

In the small station shown at E, the automobile runway 14^e is only wide enough for a single truck. The I-beams 15^e extend over the platform 10^e and over the driveway, and 30 congestion is prevented by rolling the removable bodies on the platform when necessary.

Having described the characteristics of the embodiment of my invention as illustrated, I will now explain a typical operation thereof, with reference particularly to Figs. 1, 2 and 5. Suppose a train of freight cars arrives at the terminal station A, and each car contains package freight for various 40 destinations. Various empty automobile bodies 18 are supported each by a pair of adjacent twin hoists along the opposite side of the platform. We will suppose that each of these bodies is destined for a different terminal. Now package freight is removed from each of the cars 9 and from every car some freight is taken by hand trucking (indicated by the trucks 7), to the first body 18, some to the second body, some 45 to the third body, and so on.

As soon as a truck body is loaded it is ready to be deposited on a truck proper and then carried to its destination. We will suppose that this is the condition of the 55 second body 18. Now a loaded truck arrives from another station and its driver is stopped with the truck opposite the second body. The body of the arriving truck, which may also be loaded, is now lifted 60 from the truck frame by the operation of the hoists, and is moved to idle position away from the frame, and remains suspended at the distant side of the vehicle runway, as indicated at 18^a in Fig. 2, while the 65 loaded body is racked over the truck frame

and deposited thereon, as shown at 18^b. As soon as this is done, the truck is driven away, and thereupon the body 18^a may be racked back adjacent to the platform and is then ready for unloading its freight, 70 which may be trucked across the platform to empty cars available.

The various shifts of bodies are above outlined with reference to an installation where each I-beam is provided with two twin 75 hoists, and sufficient space is provided in the vehicle runway for three truck bodies side by side. This makes a very efficient installation. Many of the advantages, however, may be obtained by a runway wide 80 enough only for two bodies, or even one body, the platform in such case being used more frequently to support bodies, which are rolled thereon longitudinally of the platform when required. This is illustrated by 85 the stations D and E in Fig. 1.

It will be understood from the above that the particular shifting for accomplishing loading and unloading varies with different installations, but the principle is maintained of removing the incoming bodies from the trucks as soon as they arrive, and depositing loaded bodies as soon as available on the frames of the trucks which have come in. There is thus maintained a continuous despatch of freight from each transfer station to all the others covered by the 95 system.

By my system, the freight arriving at a 100 terminal point for transfer to sub-stations, or to forwarding line terminal station, or transfer platform, is subject only to the delay of immediate checking, direct trucking, and storage into these removable truck bodies, plus the placing of such bodies on 105 arriving motor trucks. The frequency of such truck arrival and departure is flexible, and may be accommodated to the volume of tonnage and the interchange conditions, being readily and effectively controlled by 110 a despatcher having telephone communication with each freight house and transfer platform.

In this system, the standing or loading 115 time of the motor trucks is minimized to the last degree, and they can be constantly employed in profitable day service in shuttle movement over the city streets, as often as the removable body loads may demand. By replacing the present restricted nightly 120 movement by rail transfer by continuous day movement by motor trucks, I effect a time economy practically equivalent to twenty-four hours at each terminal or transfer point in the movement of freight, I 125 accomplish the transfer at a less expense than by rail, and I release the now employed freight cars and station and terminal yard rails for the make-up and movement of more profitable main line freight cars. 130

Having thus described my invention, what I claim is:

1. The process of transferring freight from one station to another, which comprises conveying freight from railway cars and assembling it in a unit package or mass, hoisting the package and depositing it upon transporting means, transporting the package to another station, hoisting it from the transporting means, and dispersing the contents.

2. The process of transferring freight from one city station to another, which comprises conveying freight from railway cars and assembling it in a unit package or mass, hoisting the package and depositing it upon transporting means, transporting the package over city streets to another station, hoisting it from the transporting means, and dispersing the contents to other railway cars.

3. The method of transferring freight, comprising transporting it from various railway cars across a platform, assembling it in a unit package, laterally shifting the package and lowering it onto a transporting device adapted to travel in city streets, transferring the package by means of said transporting device to another station, hoisting the package from the transporting device, and dispersing the contents to other railway cars.

4. The method of transferring freight, comprising transporting it from various railway cars across a platform, assembling it into a unit package, laterally shifting the package and lowering it onto a transporting device, transporting the package by means of said transporting device to another station, hoisting the package from the transporting device, and dispersing the contents.

5. The method of transferring freight, comprising transporting it from various railway cars across an adjacent platform, assembling it into a carrier suspended at another edge of the platform, then hoisting the carrier and depositing it upon transporting means adapted to travel in city streets, transporting the carrier to another station, removing the carrier from the transporting means, and subsequently unloading the contents of the carrier.

6. In a freight transferring apparatus, the combination of a platform, a railway track adjacent to one edge thereof, an automobile runway adjacent to another edge of the platform, a truck adapted to operate in the runway, a plurality of removable bodies for said truck, and mechanism independent of the truck for lifting a body from the truck and moving it over the platform.

7. In a freight transferring apparatus, the combination of a platform, a railway track adjacent to one edge thereof, an auto-

mobile runway adjacent to another edge of the platform, a truck adapted to operate in the runway, a plurality of removable bodies for such truck, overhead mechanism for lifting a body from the truck and moving it onto the platform, and wheels on said body whereby it may be rolled into a different position on the platform.

8. In a freight transfer system, the combination of a raised platform, a freight track on one side thereof, a set of interchangeable bodies, means for suspending them along the edge of the platform on the other side from the freight track, a vehicle runway below such suspended bodies, and a truck adapted to drive in such runway beneath the bodies, and mechanism for operating the suspended means to raise and lower the selected body from and onto the truck and for transporting it onto and from the platform.

9. In an apparatus for transferring freight, the combination of a platform, a railway track along one edge thereof, an automobile runway, a truck adapted to operate in said runway, a plurality of removable bodies, adapted to be interchangeably mounted on said truck, and hoisting means for the body having provision for raising the body from the truck and lowering it onto the truck and enabling it to be swung horizontally into various positions at an angle to the edge of the platform.

10. In an apparatus for transferring freight, the combination of a platform, a railway track along one edge thereof, an automobile runway, a truck adapted to operate in said runway, a plurality of removable bodies, adapted to be interchangeably mounted on said truck, and trolley hoisting mechanism having provision for raising and lowering the body and moving it onto and off of the platform, said mechanism being arranged to enable the swinging of the suspended body horizontally into various positions at an angle to the edge of the platform.

11. The combination of a raised platform, a railway track on one side thereof, an automobile runway on the opposite side of the platform, a truck adapted to operate in the runway, a plurality of removable and interchangeable bodies for the truck, and overhead mechanism adapted to lift a removable body from a truck and suspend it along the platform edge and over the runway with the floor of the body substantially on a level with the platform.

12. The combination of a raised platform, a railway track on one side thereof, an automobile runway on the opposite side of the platform, a truck adapted to operate in the runway, a plurality of removable and interchangeable bodies for the truck, mechanism

adapted to lift a removable body from a truck and support it with its floor substantially on a level with the platform, or raise it higher than the platform, said removable bodies having wheels at their bases adapted to support the truck on the platform and enable them to be rolled thereon.

13. In an apparatus for transferring freight, the combination of a platform, a railway track along one side thereof, an automobile runway along the opposite side thereof, a trolley trackway extending over both the platform and the runway, a trolley hoist on said track way, an automobile truck adapted to operate in the runway, and a plurality of removable and interchangeable bodies adapted to be carried by the truck and to be raised and transported over the platform by the trolley hoist.

20 14. In an apparatus for transferring freight, the combination of a platform, a railway track along one side thereof, an automobile runway along the opposite side thereof, a trolley trackway extending over both the platform and the runway, a trolley hoist on said trackway, an automobile truck adapted to operate in the runway, and a plurality of removable and interchangeable bodies adapted to be carried by the truck 25 and to be raised and transported over the platform by the trolley hoist, each truck body having wheels in its base by which it may be supported on the platform and rolled longitudinally thereon.

35 15. In an apparatus for transferring freight, the combination of a platform, a railway track along one side thereof, an automobile runway along the opposite side thereof, a pair of parallel trolley trackways 40 extending over both the platform and the runway, trolley hoist mechanism on each of said trolley trackways, an automobile truck adapted to operate in the runway, a plurality of removable and interchangeable bodies 45 adapted to be carried by the truck, and means whereby the hoist mechanisms may engage said bodies on opposite sides of the center and transport them over the platform.

50 16. A transfer system for freight terminals comprising a plurality of stations each having a platform, an adjacent automobile runway, a trolley trackway extending over the runway, and trolley hoisting mechanism 55 on the trackway, combined with a motor truck, and a plurality of removable and interchangeable bodies for said truck adapted to be supported and transported by said trolley hoisting mechanism, said trolley trackway extending for a distance at least twice the width of a removable body whereby a removable body may be trolleyed out of the way of a truck.

60 17. In a transfer system for freight termi-

nals, the combination with a plurality of 65 stations each having a platform and an automobile runway, a railroad track associated with at least one of said stations and adapted to carry freight cars on a hand-trucking level with the platform thereof, a 70 motor truck adapted to travel between the stations, a plurality of removable bodies therefor, and mechanism at each station for raising said bodies and moving them from said truck onto the platform and vice versa. 75

18. A transfer system for freight terminals comprising a plurality of stations each having a freight platform, a railroad track alongside of the same, an automobile runway adjacent to the other side of the track, 80 a supporting trackway for a trolley hoist extending over such runway and extended far enough to enable a body to be trolleyed free from a truck at the platform edge, and trolley hoisting mechanism on such supporting trackway, combined with a motor truck and a set of interchangeable bodies therefor adapted to be supported and shifted by said trolley hoisting mechanism.

19. In a freight transfer system, the combination with a plurality of stations each provided with a freight platform and an adjacent automobile runway, a trolley hoist, a supporting trackway for said hoist associated with said station and extending 95 above the platform and above the runway, a motor truck, and a plurality of removable bodies therefor adapted to be supported and transported by said trolley hoist.

20. A transfer system for freight terminals comprising a plurality of stations each having a freight platform, an automobile runway alongside of the platform, a supporting trackway for a trolley hoist extending at right angles to the platform and over 100 the platform and over such runway, trolley hoisting mechanism on such supporting trackway, a motor truck, and a set of interchangeable bodies therefor adapted to be supported and shifted by said trolley hoist- 105 110 mechanism.

21. The combination, with a plurality of stations each having a freight platform and a railway track on one side thereof and an automobile runway on the other side, of a 115 set of removable truck bodies, trolley hoisting mechanism extending over the platform and over the runway and adapted to raise and support the bodies, and a truck adapted to stand on the runway and receive and 120 transport any of the bodies.

22. In a freight transfer system, a plurality of stations each having a freight platform and a set of trolley trackways extending at right angles to the platform and arranged in pairs, there being space beneath such trackways for automobile trucks, and trolley hoists on the trackways combined 125

- with an automobile truck and a set of removable bodies each adapted to be supported and shifted by the trolley hoists on a pair of said trackways.
5. 23. The combination with a plurality of freight stations, each having a platform and an automobile runway and a pair of supporting trolley trackways extending above the runway, a pair of mutually independent dual hoists mounted on said trackways respectively, a motor truck, and a plurality of removable bodies therefor each adapted to be supported by the four lifting members of said pair of dual hoists.
10. 24. The combination with a freight platform, of a pair of trolley trackways extending at right angles thereto and above a space for vehicles, independent hoisting devices on said trackways, respectively, each hoisting device having two flexible lifting members and means for operating them as a unit, and a set of removable bodies provided with means adjacent to their corners whereby they may be engaged and lifted by such four flexible members.
15. 25. The combination with a station platform, of trolley trackways overhanging an adjacent space and arranged in pairs, a set of removable truck bodies of a length somewhat greater than the distance between the trackways of a pair, and trolley hoists on said trackways adapted to engage the removable bodies on both sides and adjacent to their ends.
20. 26. The combination with a station platform, of trolley trackways at right angles to the platform arranged in pairs, an automobile truck, a set of removable and interchangeable bodies therefor, and trolley hoists on said trackways, each hoist being provided with two lifting members raisable as a unit and adapted to engage opposite sides of the removable body adjacent to one end thereof.
25. 27. The combination with a platform and an adjacent automobile runway, of supporting trolley trackways arranged in pairs and adapted to extend from above the platform over the automobile runway, a twin-hook hoist on each trackway, a motor truck, and a plurality of removable bodies therefor each adapted to be supported by the four lifting members of said pair of twin-hook hoists, and means for moving each twin-hook hoist as a unit laterally on its trackway.
30. 28. In a freight transfer system, the combination with a platform having an adjacent automobile runway, of a motor truck adapted to stand in said runway and a set of removable interchangeable truck bodies, and mechanism to engage said bodies at four points respectively and raise, lower and transport the bodies, said mechanisms being arranged in pairs operating independently of each other and each pair having two members engaging the body and operating as a unit.
35. 29. In a freight transfer system, the combination with a platform and an automobile runway, of a pair of overhead trolley trackways overhanging the runway, a truck having a removable body adapted to stand beneath such trackways, a hoisting mechanism on each trackway each provided with a pair of lifting members adapted to engage said removable body, and means whereby the two lifting members which engage the same end of a body may be raised and lowered and transported laterally as a unit while the lifting members which engage the different ends of the body may be operated independently of each other.
40. 30. In a freight transfer system, the combination of a raised platform, a vehicle runway alongside thereof, a pair of trolley trackways extending from the platform over the runway, and a dual hoist on each trolley trackway, each hoist comprising a frame, trolleys supporting it, two lift wheels carried by the frame, lift chains running from the lift wheels, means for operating the lift wheels concurrently, each of said hoist frames being shiftable independent of the other to enable ready engagement at four points with a vehicle body out of parallelism with the platform.
45. 31. In a freight transfer system, the combination of a raised platform, a vehicle runway at the side thereof, a pair of trolley trackways extending over the runway, a dual hoist on each trackway, each hoist having a pair of flexible lifting members and means for concurrently raising them, a hand chain adjacent to the platform for operating each dual hoist independent of the other, and means for independently shifting said hoists.
50. 32. The combination with a platform and a runway alongside thereof, of overhead trolley trackways arranged in pairs overhanging the runway and a portion of the platform, hoisting mechanisms on each trackway, each provided with two flexible lift members operated as a unit, a set of removable interchangeable truck bodies each provided with means for engagement with the four lift members of the two pairs of hoists and each having rollers in its base whereby it may be rolled on the platform after being deposited thereon by the trolley hoisting mechanism.
55. 33. In an apparatus for transferring freight between distant railway cars, the combination of two railway platforms, railroad tracks each adjacent to one edge of one of the platforms, a set of removable automobile bodies, means for suspending

the bodies adjacent to another edge of each of said platforms, comprising trolley hoisting mechanism associated with each railway station, means for trucking the freight across the platform from the railway cars to the removable bodies and vice versa, and an automobile truck adapted to receive a

loaded body through the instrumentality of the trolley hoisting mechanism at either station and transport it to the other.

10

In testimony whereof, I hereunto affix my signature.

BENJAMIN F. FITCH.
